United States Patent Office.

WILLIAM MOLLER, OF NEW YORK, N. Y.

Letters Patent No. 61,851, dated February 5, 1867.

IMPROVEMENT IN COOLING ANIMAL COAL.

The Schedule referred to in these Letters Patent and making part of the same.

TO ALL WHOM IT MAY CONCERN:

Be it known that I, WILLIAM MOLLER, of New York, in the county and State of New York, have invented a new and improved "Arrangement for Cooling Animal Coal;" and I do hereby declare that the following is a full, clear, and exact description of the construction and operation of the same, reference being had to the annexed drawings, and to the letters of reference marked thereon.

Figure 1 represents a cross-section; and

Figure 2, a top view of my improved arrangement.

Animal coal, after being reburned, requires to be perfectly cooled before the same can be used in the filters. For that purpose, the coal is spread out usually in thin layers upon the floor, and is there occasionally shuffled over until cooled off. By this operation, much coal dust is made, which is consequently a great loss. To obviate this handling and shuffling of the coal, and to prevent as much as possible the making of coal dust, forms the nature of my invention.

For this purpose I arrange on the floor A diagonal plates, B B, which may be fastened perfectly tight to the floor A, as well as to the sides of the building C C. To the inside of those plates B, I attach plates D, so as to form, together with the upper parts of the plates B, small chambers. The bottoms of those plates D are cut out so as to form large openings, m, to allow the coal to fall out easily from the upper chambers E into the lower chambers F, formed by the lower part of the plates B. The upper edges of the plates D may be arranged so as to form a rail-track for a coal car to run upon. On the bottom of the chambers F, below the floor A, pipes G are attached, at suitable distances apart, to draw off the coal contained in those lower chambers F. The reburned coal is brought from the oven, and emptied into the upper chambers E; the same falls then through the openings m into the lower chambers F, and is then taken away from those chambers F when perfectly cooled, through the pipes G. By this arrangement of the diagonal plates B and D, forming several chambers, the coal is made to pass slowly from one chamber into the other chamber in thin layers, and is subjected to the cold atmosphere not only on the surface, but likewise where in contact with the plates B or D, and for which purpose a current of cold air may be forced into the chambers H, outside of the plates B, as well as into the upper part of the chambers F to cool the plates B and D.

What I claim as my invention, and desire to secure by Letters Patent, is—

The arrangement and combination of the diagonal plates B and D, forming chambers for the purpose of facilitating the cooling of animal coal, substantially as set forth and described.

WILLIAM MOLLER.
